Attorneys.

UNITED STATES PATENT OFFICE.

JEROME B. BROWN, OF BALTIMORE, MARYLAND.

DESIGN FOR BOTTLE.

Specification forming part of Design No. 6,141, dated September 17, 1872.

To all whom it may concern:

Be it known that I, JEROME B. BROWN, of Baltimore, in the county of Baltimore and in the State of Maryland, have invented a certain new and useful Design for Bottles; and do hereby declare that the following is a full, clear, and exact description thereof, reference being had to the accompanying drawing and to the letters of reference marked thereon making a part of this specification.

The nature of my design is fully illustrated by the accompanying drawing, to which reference is made.

A represents the body of the bottle, which is slightly tapering from the bottom upward, or from *a* to *b*. From *b* to *d* the outside of the bottle is concave, the diameter at *d* being smaller than that at *b*. Above the point *d* is the

neck *B*, which contracts rapidly from *d* to *e*, and from this point upward the neck is straight and provided with one or more circumferential bulges, ribs, or bands *f*, and at the top is also a band, *h*.

The body *A* of the bottle may be plain, if desired; or any letters, figures, words or characters may be blown or molded in the same.

What I claim is—

The design for bottle, substantially as shown and described.

In testimony that I claim the foregoing I have hereunto set my hand this 26th day of August, 1872.

J. B. BROWN.
